UNITED STATES PATENT OFFICE

2,076,583

TYPEWRITER ADJUSTMENT AND SHUTTER BED

Chester A. Macomic, Chicago, Ill., assignor to Macomic Corporation, Chicago, Ill., a corporation of Delaware

Application August 7, 1935, Serial No. 35,111

19 Claims.

(Cl. 276—3)

My invention relates to pattern setting mechanism adaptable for use with type casting or type setting machines and has one object to provide, in combination with a pattern bed, means adapted to be controlled by a typewriter keyboard, and means for adjusting the pattern bed actuating mechanism to the typewriter. Another object is a provision of improved means for the mounting and support of such pattern bed actuating mechanism. Another object is the provision of improved means for the support of the pattern bed. Other objects will appear from time to time in the course of the specification and claims.

I illustrate my invention more or less diagrammatically in the accompanying drawings, wherein:

Figure 1 is a side elevation with parts broken away;

Figure 2 is a side elevation with parts of the structure swung into a different position;

Figure 3 is a fragmentary vertical section with parts in side elevation;

Figure 4 is a plan view of a shutter bed, with parts broken away;

Figure 5 is a section on the line 5—5 of Figure 3;

Figure 6 is a section on the line 6—6 of Figure 5;

Figure 7 is a detail; and

Figure 8 is a section on the line 8—8 of Figure 3.

Like parts are indicated by like symbols or characters throughout the specification and drawings.

Referring to the drawings, A indicates any suitable base or support or frame member. Projecting upwardly from the base A are a plurality of hinge legs or brackets A¹. Extending upwardly from the base A at a point spaced from A¹ are other pivot brackets indicated as A². Positioned between the members A¹ and A² are one or more supporting abutments or rests A³.

Pivoted as at B¹ to the members A¹ is the typewriter supporting frame B. Mounted upon it and secured thereto is a typewriting mechanism generally indicated as B², in the present instance being simply a more or less schematic showing of the usual commercial typewriter. It has a plurality of keys B³ mounted on and actuating levers B⁴. The frame B, upon which the typewriter B² rests, normally lies in the horizontal position in which it is shown in Figure 1. It may be supported in such position as by the downwardly extending projection or abutment

portion or portions B⁵. These may be in the form of legs at the corners of the frame B.

Secured to the frame B, as by the screws C¹, is the shutter bed frame generally indicated as C, which is in the form of a rectangular frame structure as is clear from Figure 4. It is formed of four angle members, respectfully indicated as C², C³, C⁴, and C⁵. Pivoted to and between the members C² and C⁴ are a plurality of shutters indicated as C⁶. They are shown as pivoted for example on pins C⁷. Each shutter is provided with an upwardly extending lug C⁸ apertured to receive loop C⁹ of a rod or wire C¹⁰. Clips C¹¹ close each such loop. Each rod or wire is normally edged toward the left, referring to the position of the parts as shown in Figure 3, by a spring C¹², positioned exterior to the angle C³ and confined between it and any suitable adjustable stop or head C¹³ on the rod. The opposite end of each rod is pivoted to a bell crank lever C¹⁴, which is pivoted as at C¹⁵ in a cross member or comb C¹⁶. C¹⁷ indicates a second comb, mounted on the typewriter B², through which passes the levers B⁴. The comb C¹⁷ also guides the upper ends C¹⁸ of the bell crank levers C¹⁴. It will be understood that as each typewriter key is depressed, as shown at x in Figure 3, the particular lever B⁴ rides down in the comb C¹⁷ and thrusts down with it the upper arm of one of the bell crank levers C¹⁴ and thereby draws its particular rod C¹⁰ to the right, against the compression of its spring C¹². This movement of the rod rotates one of the shutters in clockwise direction into the depressed position in which it is shown as at X¹ in Figure 3. It will be understood that there is a rod C¹⁰ for each shutter, and only one shutter for each rod. Therefore, each key of the typewriter controls a single and different shutter member C⁶.

In particular relation to the adjustment of this structure to a particular typewriter, I provide, on the angle C⁵, guide blocks D. These guide blocks may be grooved or recessed as at D¹ to receive projecting lugs D², which extend outwardly from the ends of the comb member C¹⁶. The upper edge of the comb C¹⁶ is grooved as at D³. The pivot C¹⁵, in the form of a pivot rod, lying in said groove D³. A cover and securing plate D⁴ is superposed upon the comb C¹⁶ and conforms to it in shape, its prongs being effective to close the top of the channel or channels D³, whereby the member C¹⁵ is held against upward movement. Positioned adjustably upon the top of the plate D⁴ is an additional plate D⁵, which serves as a limit for upward movement of the

upper arms C^{18} of the bell crank levers C^{14} . It is adjustable, being provided with elongated apertures D^6 through which pass securing screws D^7 , which screws pass through the plate D^4 and 5 are in screw fitted relation with the comb C^{16} .

The comb C^{16} is vertically adjustable in relation to the angle C^8 and the blocks D . This vertically adjustable cone will be clear for example from Figure 8. D^8 are vertical adjusting screws, 10 bearing upon the angles C^2 and C^4 . Their rotation in one direction raises the comb C^{16} and their rotation in the opposite direction lowers it. In order to lock the member C^{16} in a locking position, I provide locking screws D^9 which are screw 15 fitted in the blocks D , which will be clear from Figures 4 and 8. The heads of the screws D^9 bear against the upper edge of the comb C^{16} , as is probably best shown in Figure 8. It will be understood that I may thus adjust the levers C^{16} 20 in relation to the typewriter levers B^4 . This adjustment is very important because the arc of movement and the location of the levers B^4 may vary from machine to machine and it is important that I be able to use my device with any ordinary commercial typewriter. This adjustment is important in connection with governing the 25 arc of movement of the shutters C^6 in response to the downward movement of the typewriter levers B^4 . Each of these shutters C^6 must terminate its downward excursion at or very close to a single given level or plane. This is important in relation to parts of the mechanism which 30 will later be described.

It is important also that I be able to lock the 35 above described actuating mechanism against movement at certain times of the operation. For example, when casting slugs when my invention is applied to type casting mechanisms. A handy way for obtaining this locking effect is to lock the bell crank lever C^{14} against retrograde movement. This, in turn, holds the rods C^{10} against movements, and holds all the shutters C^6 in raised or inoperative position. I provide for example a transverse bar E pivoted on arms E^1 for rotation 40 about the axis E^2 , which member E is shown in inoperative position in Figure 6. In order to swing the member E into locking position, I provide a link E^3 pivoted as at E^4 to a lever E^5 which, in turn, is secured to a lever E^6 pivoted as at E^7 . 45 Pivoted to the upper end of the lever E^6 is a bar E^8 which may be notched as at E^9 to receive the spring thrust plunger E^{10} . It will be clear, as from Figure 3, that when the plunger E^{10} penetrates one of the notches E^9 , the member E will be in locking position. When it engages the other of the notches E^9 the member E will be in unlocking position. Any suitable means may be employed for moving the lever E^6 into and out of locking position. I illustrate for example a pull bar E^{11} , the 50 details and actuation of which do not of themselves form part of the present invention. The pull bar E^{11} may be moved to the left, referring to the position of the parts in Figure 3, to rotate the upper end of the lever E^6 to the right and 55 therefore to move the member E into locking position. A pull on the rod E^8 , in the opposite direction, will move the member E into unlocking position.

Positioned beneath the above described shutter 60 bed and shutter structure is a diagrammatic showing of a plunger carriage which may show for example the transverse member G . The details of the plunger carriage do not of themselves form part of the present invention, but it will be 65 understood that in any suitable guide or frame I

mount vertical movable plunger G^1 . Any suitable means may be provided for holding the plungers G^1 normally at their upper position. The entire plunger structure runs on roller G^2 , which ride on a track G^3 mounted in any suitable fashion. For example I illustrate in Figure 3 a track or rod G^3 mounted between the legs B^5 . Another rod G^4 is suspended as by links G^5 from the opposite side of the frame B . The details of this structure do not of themselves form part of the present invention. There is a single plunger G^1 aligned with each of the shutters C^6 , it being understood that the plungers will be depressed as at X^2 in Figure 3, when the corresponding shutter is actuated. The plunger carriage and plungers ride along tracks G^3 and G^4 in response to rotation of a lever G^7 , which lever is pivoted as at G^8 intermediate its ends and is moved by the progressive movement of the typewriter carriage. In other words, every time the operator strikes a 20 key the typewriter carriage is moved a single step and its movement moves the plunger carriage structure G a single step.

Pivoted to supports A^3 and resting upon the abutments A^3 is the pattern bed generally indicated as H . The details of this bed do not of themselves form part of the present invention, but it will be understood that the bed supports, in vertically movable position, a plurality of pattern pins H^1 . These pins are vertically movable and the frictional relation between them and the bed is such that they will normally keep the position to which they have been moved, until they are positively moved to some other position. I illustrate the pins as formed in pairs, each pair 35 having opposed recesses H^{10} , which together receive an elevating bar H^2 . These bars are connected at the ends as by transverse connecting members H^3 , which in turn may be elevated as by rotation of the bell crank levers H^4 at their upper arms H^5 . The bell crank levers are connected as by a transverse actuating bar H^6 . It will be understood that a movement of the bar H^6 to the right, referring to the position of the parts as shown in Figure 1, will raise the bar structure H^2H^3 and 40 raise all the stop pins H^1 .

Each pair of pins H^1 is controlled by a single plunger G^1 and through it by a single shutter C^6 . This is because of the current custom of employing a typewriter shift. For example when 45 the typewriter is normally operating, the plunger structure G may be in the position in which it is shown in Figures 1 and 3. If the operator shifts to caps the shift lever actuates a rod H^{10} which has for effect to impart to the entire plunger carriage a longitudinal movement. When actuated, the particular plunger X^2 for example, referring to Figure 3, would be shifted from opposition to the pin which is shown depressed in Figure 3 and would depress the adjacent pin of the pair. 50

It will be realized that whereas I have described and shown a practical and operative device, nevertheless many changes may be made in size, shape, number and disposition of parts without departing from the spirit of my invention. I 55 wish my drawings to be taken, therefore, as in a broad sense illustrative and diagrammatic, rather than as limiting me to the specific details and relations of parts herein shown.

Whereas I have illustrated my invention as applying to a line of type casting or type setting machine, it will be clear that the same or similar mechanism or the same principles may be used in connection with a large number of devices where- 60 in a shutter bed or a pattern bed can be employed 70

to control the movement of parts of mechanisms. And where in the specification and claims I use language directed to type setting or type casting, I wish it understood that such language is used 5 primarily for purpose of illustration, not to narrow the field or intent of my invention.

The use and operation of my invention are as follows:

I illustrate it as applying to a class of structure wherein an ordinary commercial typewriter 10 may be employed in either type setting or type casting. I obtain this result as follows:

The depression of a typewriter key B⁴ depresses the upper arm C¹⁸ of a bell crank lever 15 and moves the lower arm C¹⁴ to the right, referring to the position of the parts as shown in Figures 1 and 3. This moves one of the rods C¹⁰ to the right and depresses one of the shutters C⁶. This in turn depresses a plunger G¹, and 20 the plunger depresses a pin H¹. It will be understood that whereas there is but a single row of plungers G¹ which move progressively across the top of the pattern bed, there are aligned pins or pairs of pins H¹ all the way across the pattern bed. There are as many or substantially as many pins in each row as there are symbols available on the typewriter. Thus, in each row the operator can depress the pin corresponding to any symbol on his typewriter. Each stroke of 30 the key depresses one pin. The carriage is moved forward one step. The movement of the carriage moves the plunger carriage forward one step, and the plunger carriage and single row of plungers are therefore aligned with a new row of 35 pins. The operator then strikes a key and depresses one pin. This process continues, it being possible to depress one pin only of each row of pins. As above mentioned, the typewriter shift lever controls a rod H²⁰, which rod is actuated 40 in response to rotation of the bell crank lever H²¹, as shown for example in Figure 3.

After the operator has written a full line, namely, has depressed, if he wishes, one pin in each of the rows of pins, he is ready to set or 45 cast type. However, the type casting or type setting mechanism does not of itself form part of the present device, it being understood that any suitable means may be employed, responsive to the downward projection of the pins, for actuating whatever type setting or type casting mechanism is provided. Thereafter the rod H⁶ is employed to return the pins to their upward position. Each plunger G¹ is automatically returned to its upper position as soon as the overlying 50 shutter C⁶ permits and each shutter C⁶ is always in its upper or inoperative position unless the corresponding key of the typewriter is actually depressed.

The present structure is particularly advantageous, in that the intermediate shutter plunger and pattern structure may be adjusted to any ordinary type of typewriter, an adjustment of the arc of movement of the shutter C⁶ being possible. I also provide means for locking the shutter structure against movement. It is furthermore advantageous to provide pivotal supporting means for both the shutter bed and the pattern bed, so that each may readily be moved or pivoted into position as shown in Figure 2 where 65 the operator, service man, or repair man, can have ready access to the bottom of the parts.

I claim:

1. In combination, a base, a pattern bed including a pattern frame and a plurality of pattern pins movable in said frame and a pivotal

connection between said pattern bed and said base, whereby the bed may be rotated in relation to said base.

2. In combination, a base, a pattern bed including a pattern frame and a plurality of pattern pins movable in said frame and a pivotal connection between said pattern bed and said base, whereby the bed may be rotated in relation to said base, and means for supporting said bed in predetermined position in relation to said base. 10

3. In combination, a base, a pattern bed rotatably mounted upon said base, means for holding said pattern bed in predetermined relation to said base, a shutter bed, rotatably mounted 15 upon said base and means for holding said shutter bed in predetermined position, above said pattern bed.

4. In combination, a base, a pattern bed rotatably mounted upon said base, means for holding said pattern bed in predetermined relation to said base, a shutter bed, rotatably mounted 20 upon said base and means for holding said shutter bed in predetermined position, above said pattern bed, the axes of rotation of the pattern bed and of the shutter bed being along opposite edges. 25

5. In combination, a base, a pattern bed rotatably mounted upon said base, means for holding said pattern bed in predetermined relation to said base, a shutter bed, rotatably mounted 30 upon said base and means for holding said shutter bed in predetermined position, above said pattern bed, including a base engaging abutment associated with the shutter bed.

6. In combination, a base, a pattern bed rotatably mounted upon said base, means for holding said pattern bed in predetermined relation to said base, a shutter bed, rotatably mounted 35 upon said base and means for holding said shutter bed in predetermined position, above said pattern bed, and a plunger carriage mounted upon said shutter bed. 40

7. In combination, a generally horizontal base, a pattern bed including a pattern frame and a plurality of pattern pins movable in the frame, a pivotal connection between said pattern bed and said base, whereby the bed may be rotated in relation to said base, a supporting abutment adapted to support the pattern bed in generally horizontal position in general parallelism with 45 the upper surface of said base, a frame, pivoted to said base, and adapted, when in one position, to overlie said pattern bed, a typewriter mounted upon said last mentioned frame and actuating means for said pattern pins, mounted on said frame, including a plurality of shutters, and means for actuating said shutters in response to 50 actuation of the typewriter keys. 55

8. In combination, a generally horizontal base, a pattern bed including a pattern frame and a plurality of pattern pins movable in the frame, a pivotal connection between said pattern bed and said base, whereby the bed may be rotated in relation to said base, a supporting abutment adapted to support the pattern bed in generally 60 horizontal position in general parallelism with the upper surface of said base, a frame, pivoted to said base, and adapted, when in one position, to overlie said pattern bed, a typewriter mounted upon said last mentioned frame and actuating means for said pattern pins, mounted on said frame, including a plurality of shutters, and means for actuating said shutters in response to 65 actuation of the typewriter keys, and means for locking said shutters against actuation. 70

9. In combination, a base, a pattern bed mounted on said base, a plurality of pattern pins axially movable in said pattern bed and means for moving them, including a plurality of rotatably mounted shutters, and means for rotating them including a typewriter having keys and key levers and an actuating connection between said key levers and said shutters, and means for varying the arc of rotation of said 10 shutters.
10. In a shutter bed for use with a typewriter having keys and key levers, a plurality of shutters rotatably mounted in said bed, a control rod connected to each shutter, a lever associated with each control rod, each such lever being aligned with a typewriter key lever, and means for unitarily adjusting the height of said rod levers.
11. In a shutter bed for use with a typewriter having keys and key levers, a plurality of shutters rotatably mounted in said bed, a control rod connected to each shutter, a lever associated with each control rod, each such lever being aligned with a typewriter key lever, and means for unitarily adjusting the location of the axes 20 of rotation of said rod levers, including a member upon which said rod levers are rotatably mounted and means for varying the height of said member in relation to the typewriter.
12. In a shutter bed for use with a typewriter 25 having keys and key levers, a plurality of shutters rotatably mounted in said bed, a control rod connected to each shutter, a lever associated with each control rod, each such lever being aligned with a typewriter key lever, and means for unitarily adjusting the location of the axes 30 of rotation of said rod levers, including a member upon which said rod levers are rotatably mounted and means for varying the height of said member in relation to the typewriter, and 35 means for locking such member in adjusted position.
13. In a shutter bed for use with a typewriter having keys and key levers, a plurality of shutters rotatably mounted in said bed, a control rod connected to each shutter, a lever associated with each control rod, and means for unitarily adjusting the location of the axes of rotation of said rod levers, including a member upon which 40 said rod levers are rotatably mounted and means for varying the height of said member in relation to the typewriter, and means for locking such member in adjusted position.
14. In a shutter bed for use with a typewriter having keys and key levers, a plurality of shutters 45 movably mounted in said bed, a control member associated with each shutter, a control lever associated with each such member and adapted to be actuated in response to movement of the typewriter key levers, and means for unitarily varying the location of said control levers.
15. In a shutter bed for use with a typewriter having keys and key levers, a plurality of shutters 50 movably mounted in said bed, a control member associated with each shutter, a control lever associated with each such member and adapted to be actuated in response to movement of the typewriter key levers, and means for unitarily varying the location of said control levers.
16. In type selecting machines and the like, a pattern bed having a plurality of movable pattern forming members, a typewriter and connecting means interposed between it and the pattern bed for displacing selected pattern forming members responsive to the striking of individual typewriter keys, and a support upon which the pattern bed is mounted for movement into and out of working relationship with the typewriter and connecting means.
17. In type selecting machines and the like, a pattern bed having a plurality of movable pattern forming members, a typewriter and connecting means interposed between it and the pattern bed for displacing selected pattern forming members responsive to the striking of individual typewriter keys, the pattern bed being movable and means for holding it in working relationship with the typewriter and connecting means.
18. In type selecting machines and the like, a pattern bed having a plurality of movable pattern forming members, a typewriter and connecting means interposed between it and the pattern bed for displacing selected pattern forming members responsive to the striking of individual typewriter keys and a support upon which the pattern bed is mounted for movement into and out of working relationship with the typewriter and connecting means, and a stop in the path of the pattern bed adapted to arrest its movement and hold it in working relationship with respect to the typewriter and the connecting means.
19. In type selecting machines and the like, a pattern bed having a plurality of movable pattern forming members, a typewriter and connecting means interposed between it and the pattern bed for displacing selected pattern forming members responsive to the striking of individual typewriter keys, the connecting means including a plunger carriage mounted for travel in consonance with the typewriter carriage, a shutter bed including a plurality of shutters adapted one to cooperate with each plunger on the plunger carriage, connecting means between the typewriter keys and the shutters, the plunger carriage being adapted to move in a plane generally parallel with the pattern bed, a support upon which the pattern bed is removably mounted and means in the path of the plunger bed for arresting its movement toward and holding it in working relationship with respect to the plunger carriage.

CHESTER A. MACOMIC.
